**KINETOGRAPH MOVEMENT DRIVING
 MECHANISM**
 George A. Mitchell, 687 Prospect Crescent,
 Pasadena, Calif.
 Filed Aug. 5, 1963, Ser. No. 299,796
 17 Claims. (Cl. 226—57)

This present application is a continuation in part of my previous application Serial No. 267,478, filed March 25, 1963 now abandoned, for Register Actuation for Kinetograph Movement.

This invention has to do with a novel cam mechanism for driving elements, such as registration members and claw arms, of movements for kinetograph mechanisms. That prior application described one form of my cam mechanism driving an improved form of pilot pin device. The present application adds to that disclosure another form of the novel cam mechanism, the driving of the pilot pin device by that other form, and the driving of a film moving claw arm by both forms of the cam mechanism.

In the improved driving cam mechanism the cam element or unit, drives the driven element, such as pilot pin or claw arm with relatively long stationary dwells and very fast movement strokes, and with the driven element constantly held against loose movement between two opposed followers. The fast movement strokes, which involve slow rather than sudden acceleration and deceleration, are due to cooperating configurations of the cam element and the follower elements, as will be developed below. As an example, with the present cam mechanism the film moving stroke of a claw arm may typically occupy as little as 22° of driving shift and shutter rotation, leaving as much as 320° for total shutter opening with an allowance of 18° for shutter safety.

The characteristics of the invention will best be understood from the following descriptions of typical forms of cam elements driving cooperating follower elements which drive such driven elements as pilot pin and claw arm. Reference is had to the typical and illustrative embodiments shown in the accompanying drawings, in which:

FIG. 1 is an elevation showing the application of the present improvement to a film registration element also of improved design;

FIG. 2 is an end elevation of the same;

FIGS. 3 and 3a are sections on line 3—3 of FIG. 2, showing the register element, respectively in and out of film engagement;

FIG. 4 is a section on line 4—4 of FIG. 3;

FIG. 5 is a schematic view similar to FIG. 3 showing a modified cam mechanism;

FIG. 6 is a section on line 6—6 of FIG. 5;

FIG. 7 is a general elevation showing a claw arm movement in its position of upper dwell shortly before the start of its film-moving down stroke, driven by the type of cam mechanism shown in FIGS. 3, 3a;

FIG. 8 is a section on line 8—8 of FIG. 7;

FIG. 9 is a section on line 9—9 of FIG. 7;

FIG. 10 is a schematic showing the movement at the start of the down-stroke;

FIG. 11 is a similar schematic showing the movement at the finish of the down-stroke;

FIG. 12 is a similar schematic showing the claw withdrawal at the end of the dwell at the bottom of the down-stroke;

FIG. 13 is a similar schematic showing the end of the up stroke, the upper dwell being between the positions of FIG. 13 and FIG. 10;

FIG. 14 is a side elevation similar to FIG. 7, showing the claw arm driven by the modified cam mechanism of FIG. 5 at reduced scale;

2

FIGS. 15 and 16 are sections on lines 15—15 and 16—16 of FIG. 14;

FIG. 17 is a diagram illustrating the relative movements of a cam member and follower; and

FIG. 18 is a diagram showing the resultant movement pattern of the follower plotted against cam rotation.

FIGS. 1 to 6 show the improved cam mechanism driving a film registry element in the form of a pilot pin. Reference is first made to FIGS. 1 to 4.

In those figures a movement driving shaft is indicated at 20, driving a claw arm 22 by cam operation to advance its claw or claws 24 into film perforations, then move the film F down through race 26 and then withdraw from the film and move back upward for the next cycle beginning with advance for film engagement. The nature of the improved cam drive and the claw path of the claw arm are not shown here, but in FIGS. 7 and following. The register means is here shown as embodying the usual register pin or pins 28 adapted to move in and out of film perforations, to register the film during its dwells and successive movements of the claw arm. As here shown, the register pin 28 rides flatly on a guide 30 mounted on a fixed part 32 of the film race. The pin or pins 28 are carried on the forward end of a reciprocating shaft 34 which is reciprocatingly operated by cams on driving shaft 20. Shaft 34 reciprocates in slide bearings formed in lugs 36 on fixed plate 38.

In the form of FIGS. 1 to 4 driving shaft 20 carries two register operating cams 40 and 42 which, respectively, operate on cam follower arms 44 and 46 that depend from members 48 and 50 that are generally cylindric in form and fit closely slidingly on shaft 34. The two members 48 and 50 are held in mutual endwise abutment by a spring 52 seated on snap ring 54 on shaft 34, pressing 48 against 50. Member 50 is seated against a cam member 56 which in turn is seated against snap ring 58 on shaft 34. A cam formation 60 on 50 and 56 causes relative withdrawing movement (to the right in the drawings) of shaft 34 when member 56 is swung by handle 62 about shaft 34 through a suitable angle, say of 90°. As explained later, the two cam follower arms 44 and 46 and their members 48 and 50 are held by cam engagement in a fixed position (for any angular position of the cam shaft 20) so that pilot pin 28 will be withdrawn from film engagement by swinging the camming member 56 to withdraw shaft 34 relative to the members 48 and 50. It may be remarked here that the two cams 40 and 42 form, in effect, a composite cam between the two follower arms 44 and 46. Those two arms may then be accurately fitted for close bearings on the cams by grinding and/or lapping the abutting surfaces 66 of members 48 and 50. As will be noted from the drawings, members 48 and 50 with their follower arms 44 and 46 are duplicates of each other except that, as shown, 50 has the cam formation at 60. However, member 48 may also, without harm, carry the same cam formation on its end engaged by spring 52; so that both members may be exact duplicates.

As shown in FIGS. 2 and 4, cams 40 and 42 are axially offset on shaft 20. Disks 70 lie at opposite sides of the two cams and confine follower arms 44 and 46 which are offset on members 48 and 50 corresponding to the cam offsets. Disks 70 keep the followers 44 and 46 in cam engagement, preventing them and their members 48 and 50 from swinging about register shaft 34.

As will be understood from the description thus far, the distance between the follower faces 44a and 46a of the followers 44 and 46, measured in a directional normal to the axis of shaft 20 and parallel to shaft 34, is a fixed quantity. More accurately speaking, the sum of the radial distances from that shaft axis to the planes of 44a and 46a is a fixed measure. Cam 40 operates on

follower arm 44; cam 42 on follower arm 46. And the shapes of those two cams and their follower faces are such that both cams are always in follower engagement, or least, always in such engagement during the critical periods of register operation.

FIGS. 3 and 3a show the positions of cams 40 and 42 in the middles of their positions for, respectively, pilot pin fully projected and fully withdrawn. Cam 40, operating on follower 44, is circular about the axis of shaft 20 from such a radial line as indicated at 80 to such a radial line as indicated at 80a. Assuming cam rotation in the direction indicated, follower 44 will be positively held to the left, with the pilot pin projected, during that cam rotation from 80 to 80a, through an angle, as here shown, of approximately 235°. Consonantly, cam 42, engaging follower 46 is circular about the shaft axis between the two radial lines indicated at 82 and 82a. The angular distances between 80, 80a and 82, 82a, are equal. The radius of the circular arc of cam 42 is less than that of the circular arc of cam 40 by an amount equal to the total cam actuated movement of the pilot shaft 34; and those two arcs are diametrically opposed about the axis of shaft 20. Consequently, pilot pin 28 is positively held immovably in its projected film-registering position during rotation of the cams through the angles mentioned.

FIG. 3a shows the cams rotated from the position of FIG. 3; in their medial position for retracting the pilot pin. In this position, a circular arc of cam 42, lying between such radial lines as indicated at 84 and 84a, engages follower 46 to hold the pilot retracted. As here shown, the angle of that arc is about 50°. As here shown, the radius of that arc about the axis of shaft 20 is the same as the radius of the circular arc of cam 40 between 80 and 80a. In this position of the cams, a diametrically opposed circular arc of cam 40, lying between the lines indicated at 86 and 86a, and also of about 50°, and of radius here shown as equal to the smaller radius of the circular arc of cam 42 that lies between the lines 82 and 82a, is in engagement with follower 44. Consequently during the angular cam rotation through the 50° angles 84 to 84a and 86 to 86a, the pilot is positively held immovably in the retracted position.

On cam 40 the runs between the smaller radius arc 86-86a and the larger radius arc 80-80a, in the aspects of FIGS. 3, 3a, are here shown as straight lines tangential to the arc 86-86a of smaller radius. Likewise, on cam 42, the runs between the smaller radius arc 82-82a and the larger radius arc 84-84a are shown as straight lines tangential to arc 82-82a. The straight line runs, as shown in FIGS. 3-3a of the two cams are diametrically opposed. Throughout the diametrically opposed rotational angles of the circular arcs on the two cams, the cam element or unit is of course of constant diameter. But the cam diameters through the shaft axis between points on the straight line runs, such as designated 87 and 87a in FIG. 3a, is not itself constant and, as pointed out later, it is the opposing convex shapes of the follower faces 44a and 46a that keep the cam unit always snugly engaged between the follower faces during those straight line runs of the cam unit, as well as during the cam rotation through the angles of their opposed circular arcs. In full effect the follower shape makes the cam mechanism to act as a constant diameter cam, as well as to give the followers slow acceleration and deceleration as hereinafter developed.

The shapes of the two cams through the rotational angles between the circular arcs, and the shapes of the followers, are so related that, during the shifts of the pilot between protracted and withdrawn positions, each cam is constantly in engagement with its respective follower; so that, at no cam position is the pilot and follower ensemble allowed to be shiftably loose and subject to chattering, etc.

The several rotational angles of the cam formations are, of course, designed to shift the pilot in synchronism with the operation of the film movement. That movement is here shown as a claw, but may be of any type. 5 As applied to a claw movement the cam angles are preferably designed to project the pilot pin into a film perforation as the claw pulls out of its engaged perforation and to withdraw from the pilot perforation as the claw moves into its next perforation preparatory to moving the film. 10 The film is thus normally continuously engaged by the claw and pilot; the cam at 60 withdrawing the pilot to free the film for threading, etc.

Although the respective major and minor radii of the two cams are here shown as equal, that is not at all necessary to the described operation of the pilot nor to that of the claw arm later described. It is only necessary that the respective differences, in the two cams, between their major and minor radii be equal. This is also true of the same type of composite cam device driving the 20 claw arm as in FIGS. 7 and following.

There are several distinct advantages inherent in the described pilot actuation by a cam unit of two cams. One is fast pilot shifting, which results in a longer period of film dwell, here approximately 235° of rotation 25 of movement shaft 20 and the associated shutter. Another lies in the positive immovable holding of the pilot in its projected film engaging position. That eliminates all sawing of the film perforations during that period of pilot projection and the accompanying film displacement due to such sawing. And the fact that the pilot is held immovably during projection, makes it possible to use registration means other than a perforation entering pilot pin. For example, a film clamping pressure foot might, on projection, clamp the film against an opposite surface 30 of the film race. Such clamping however has no function in registering the film position. The standardly used claw type movement has a claw or claws smaller in cross-section than the film perforations, to take care of film shrinkage. Thus, such a claw movement does not leave the film in registered position. Register pins, on the other hand, are of cross-sectional size in either one or both dimensions equal to the corresponding perforation 35 dimensions. With a slight forward end taper they thus move and hold the film in registered position, and for that reason are here preferred.

Each of the cam follower arms 44 and 46 has, instead of a flat inner cam contacting face, a convexly curved face such as shown at 44a and 46a. As here shown these convex lobe formations have a curvature radius approximately the same as the largest radius on the cams. The particular results of such convex cam contacting lobes are mainly due to the fact that the line or point of cam contact during cam rotation through the angles of changing radius—as for instance in the angle of approximately 35° between 80 and 86 on cam 40—that line of contact moves vertically on the contact faces 44a and 46a of 44, 46 by a much smaller amount than such movement on a flat contact face. Result is that during all angles of cam rotation the cams much more accurately fill, so to speak, the spacing between the follower contact faces, with significant reduction of chatter noise due to looseness. And the cam produced reciprocation of the register shaft and pins follows a sine curve with gradually increasing and decreasing velocities, without any sudden accelerations and decelerations. The reasons for this are more fully discussed after the later descriptions of such a driving cam mechanism applied to a claw arm.

FIGS. 5 and 6 show how the two followers 44 and 46 may be driven by a single cam 90. This cam has an arc 92 of the larger radius and of angle about 162° lying between the radial lines indicated at 94, 96. A diametrically opposite arc 93 of the smaller radius also extends through the same angle between the lines 94, 96. Between the ends of arcs 92 and 93, the cam has, as in the form 75 of FIGS. 3, 3a, a periphery of changing radius along lines

98 which are formed by straight cam faces tangent to the arc 93 of smaller radius. In FIGS. 3, 3a, the corresponding peripheries of changing radii lie between the radial lines 80-86, 80a-86a, 82-84a, and 84-82a. In FIGS. 5 and 6, the cam rotative angle of pilot pin shift is approximately 18°, between the radial lines 94-96. Here again the shift is fast and the curvatures of follower faces 44a and 46a cooperate with the cam configuration to give slow accelerations and decelerations and constant snug engagement of the cam between the followers. It has been found that the optimum in that regard is with the radius of curvature of 44a and 46a (in either these figures or in FIGS. 3, 3a) approximately equal to, but slightly greater than, the larger of the two cam radii; and the radii of 44a and 46a are here so shown. As will be further developed, a radius for 44a, 46a much larger or materially smaller than the larger cam radius leads to looseness between the cam or cam assembly during transition and to relative suddenness of acceleration and deceleration of the cam driven element.

FIGS. 7 to 13 show the application of the improved forms of cam mechanism to an improved form of film moving claw arm. In these figures the scale is approximately twice the dimensions of a design for 16 mm. film and the dimensions later noted in illustration are for such a design.

The physical form of the claw movement is shown in FIGS. 7, 8 and 9. As there shown, the claw arm consists of a plate member 120, carrying claw 122 at one end and having a sliding pivotal mounting at the other end. As shown here that sliding pivotal mounting consists of a fixed pivot pin 124 and sliding pivot ways 126 on the claw arm, although the arrangement might be reversed with pin 124 mounted on the arm and pivotally sliding in a fixed way.

Plate member 120 lies between the two complementary cams 130 and 132 fixedly mounted for rotation on and by driving shaft 134. In its portion between the two cams and around shaft 134 plate member 120 has a rectangular opening 136 accommodating a cam 138, shown as a conventional constant diameter heart-shaped cam, which acts, as will be described, to shift the claw arm for claw projection and retraction. The three cams may be fixed on shaft 134, axially and to rotate together with the shaft, in any suitable manner.

Plate member 120 also carries at its upper portion a cam follower 140 offset into the plane of cam 130 as shown in FIG. 8. Also that main plate carries another cam follower 142 at its lower portion, offset oppositely to follower 140 and into the plane of cam 132, as shown in that figure. Each of these followers has an inner curved, preferably circular cam contacting inner edge face 144, 146, typically of radii about equal to the larger radius of the two cams 130 and 132. As shown here the center of circular follower face 144 is located at 145 and that of circular follower face 146 is at 147. As here shown the centers 145 and 147 are located diametrically opposite each other about the axis of shaft 134 (except for the small amount of in and out shift) and the radii of follower faces 144 and 146 about equal to, and preferably slightly larger than the larger cam radius.

It will be noted that cams 130, 132 and 138 as well as the claw arm 120, are plate-like members. The cams may, for instance, be formed by stamping or similar operations. Claw arm member 120 may likewise be formed, with its cam followers 140 and 142 by stamping and embossing operations. All four of these members may be initially formed of some relatively soft metal, as, for example, of a soft aluminum alloy such as that known as 2024. Such an alloy may then, after formation of the parts and initial heat treatment, be surface hardened by using such a process as that known as Kanigen, followed by another and lower temperature heat treatment; so that in their finished forms all the relatively moving parts of

the claw movement are hard surface finished and long wearing.

As shown in FIG. 7, cam 130 has an arc periphery 150, here designed as of 60° extent, between the two radial lines *a* and *b*, and of what is here called the smaller radius. Leading tangentially from the ends of that arc of 60° extent, cam 130 has two substantially straight shift faces 151 and 152, leading to the ends of an arc face 154 at what is here called the larger cam radius. That larger radius arc extends around cam 130, in the design as here shown, for about 230° between the radial lines designated *e* and *f*.

Complementary to cam 130, cam 132 has an arc periphery 160, at the larger radius, between the radial lines *c* and *d* which lie diametrically opposite the radial lines *a* and *b* of cam 130. From each end of that 60° arc of larger radius cam 132 has shift faces 161 and 162 leading tangentially into the arc of cam face 164 which also extends around cam 132 for about 230°. It will be noted that the arc faces 150 and 160 on the two cams are diametrically opposed, as are also the two arc faces 154 and 164. The shift faces 151, 161 and 152, 162 are likewise diametrically opposed and of equal angular extent of about 35° each.

In an actual illustrative design, here shown at approximately twice scale, the larger cam radius is about 12.2 mm., the smaller, about 10 mm.; and the radii of the two follower faces 144 and 146, about 13.4 mm.

FIG. 10 shows schematically the position of the parts at the beginning of the film moving down-stroke. In this figure, as well as in FIGS. 7 and 11, the shift cam 138 has moved the claw arm to the left in the direction of projecting claw 122 into the film. In an actual design the throw of cam 138 is about one thirty-second inch, throwing the follower centers 145, 147 one sixty-fourth inch each side of the center line through the axis of shaft 134.

FIG. 11 shows schematically the positions of the parts at the end of the film moving down-stroke. Cam rotation in the indicated direction between FIG. 10 and FIG. 11 is about 27°. The angle subtended by the cam shift runs 151 etc. at the shaft axis is about 35°, but the claw arm has, in FIG. 11, swung about pin 124 about 8° in the direction opposite to the cam rotation. The film moving stroke thus occupies only about 27° of cam and shaft rotation, safely leaving some 320° for shutter exposure opening. In the position of FIG. 11, shift cam 138 is still holding the claw arm shifted to the left in the film.

FIG. 12 shows schematically the positions at the end of the dwell at stroke bottom, the position from which the return up-stroke then begins. In this position the cams have rotated 60° from the position of FIG. 11—through the angle between radial lines *a* and *b*—and shift cam 138 has shifted the claw arm to the right to withdraw claw 122 from the film. The exposure opening of the shutter may commence during the movement between FIGS. 11 and 12.

FIG. 13 shows the positions on reaching the top of the upward return stroke with shift cam 138 still holding the claw arm to the right. The cam rotation from the position of FIG. 12 to FIG. 13 is the angle subtended by shift runs 152, 162, about 35° plus the swing of the claw arm, making about 43° cam rotation.

From the position of FIG. 13 to that of FIG. 10 where the film moving down-stroke starts the cam rotation is more than 210°—the rotation of the radial line *e* in FIG. 13 to its position shown in FIG. 10. During that rotation shift cam 138 shifts the claw arm to the left and the claw into the film.

FIGS. 14, 15 and 16 show the single cam form of FIGS. 5 and 6 applied to the claw arm. Here the single cam 90 is of the same form as in FIGS. 5 and 6 and the same numerals are applied. The two cam followers 140a and 142a have the same follower surface radii, and are lo-

cated on the claw arm 120, in the same relative positions, as in FIGS. 7 and following, but here they both engage the single cam 90, being offset from the same face of 120 to overhang that cam. Cam 90 is attached to shaft 134 and a disk 90a also attached to the shaft may hold claw arm 120 against cam 90. The film moving stroke of the claw arm (down) occupies the same small cam rotation angle as in FIGS. 7 and following.

FIGS. 17 and 18 are diagrams illustrating the relative movements of a cam and follower. In FIG. 17 a cam shift run A extends tangentially from the arc B of smaller radius to the point C where it meets the arc D of larger radius. The radius of curvature of the follower is here indicated by the line E normal to A. That radius is here shown as the average between the radii of B and D. Assume cam rotation relative to the follower in the direction indicated, or relative follower rotation about the cam axis in the opposite direction.

Upon the follower curvature reaching the point C on the cam, the follower center then, relatively, swings in the arc E from the point F to the point G where the follower radius is normal to A. From there on the follower center moves, relatively, parallel to A to the point H. The described construction can be employed to analyze the cam action for any desired cam proportions and follower radius, the relations shown being illustrative.

The diagram of FIG. 18 shows the follower displacement relative to the cam-concentric arc J plotted against relative cam advance in the direction indicated; that relative displacement being, strictly speaking, the rectilinear displacement of a rectilinearly guided element such as the registration element of FIGS. 1 and following. As will be noted from FIG. 18, the curve K of relative follower movement is essentially sinusoidal in character and is symmetric, or nearly so, about its center at L. It follows that the two diametrically opposed followers constantly engage opposite sides of the cam device, whether a single cam or a composite one. And it is apparent from FIG. 18 that the cam driven follower movement is one of slow acceleration and deceleration. It has been found that the slight displacement of the followers relative to the cam, due to the swing of the claw arm, modifies their close cam engagement very slightly, so that even on the swinging claw arm there is no appreciable looseness between the cam element and the opposed followers. But it also has been found that decrease of the follower radii to materially less than the larger cam radius tends to introduce play during the cam stroke, while increase of the follower radii to much more than the larger cam radius introduces play during the cam stroke. It will be understood that the opposed cam followers, with their curvature centers diametrically opposed about the cam axis—the axis of driving shaft 20 or 134—have their curved cam engaging faces diametrically opposed at a distance equal to the larger cam radius plus the smaller cam radius. See, for instance, FIGS. 3 and 7.

The form of claw arm drive shown, for example, in FIGS. 7 and following may be used in combination with such a pilot pin drive as in FIG. 3. In other words, the claw arm drive of FIG. 1 may be that of FIG. 7. The rotational cam angle during which the pilot pin of FIG. 3 is in the film may easily be increased to as much as 312° or more by reducing the cam arcs between 84-84a and 86-86a to about 10°. In FIG. 7, as shown, the cam rotational angle for the film movement is 27°, leaving the film stationary for 333°. That film shifting rotational angle—the rotational angle of the shift runs 151 etc. and 161 etc.—may be increased by 20° or more by increasing the differences between what has been called the larger and smaller cam radii, making the film dwell equal to the cam-angular measure of pilot pin and film engagement.

It will be seen immediately from geometrical considerations that the cam throw equals the difference between the larger and smaller cam radii, and that the angle oc-

cupied by the cam stroke, commonly referred to as the stroke angle, is the angle whose cosine is the ratio of the smaller cam radius to the larger cam radius. That stroke angle is less by almost 30% than the stroke angle of a conventional constant width cam, sometimes referred to as heart shape, for the same ratio of larger to smaller cam radii. Hence, for a given cam size and a given throw, the cam structure of the present invention permits the very substantial reduction in throw angle of substantially 30%.

The most satisfactory follower radius for any particular cam dimensions and proportions may be determined in any desired manner, for example by calculation, by direct test, or on the basis of experience. Calculation shows that, for a constant value of the larger cam radius R_1 , the optimum value of the follower radius of curvature R_3 is a nearly linear function of the smaller cam radius R_2 . If the criterion for selection of the follower radius is taken as accuracy of fit at the start and at the end of the cam stroke, calculation indicates that the follower radius R_3 should be close to the value given by the following equation:

$$R_3 = R_1 + 0.55(R_1 - R_2) \quad (1)$$

In substance, Equation 1 states that the follower radius exceeds the larger cam radius by approximately $\frac{1}{2}$ of the difference between the two cam radii, that is, by approximately $\frac{1}{2}$ of the cam throw. When the follower radius is so chosen, the fit is typically within one or two thousandths of R_1 during the initial and final 10 or 15° of the cam stroke, that is, during the entire stroke if the stroke angle does not exceed about 25°. For larger stroke angles the cam may tend initially to become tight during the central portion of the cam stroke. Any binding due to that cause tends to disappear as the mechanism is broken in, presumably as the cam corners become very slightly rounded.

On the other hand, if the criterion is taken as the maintenance of accurate cam fit at the mid-point of the stroke, calculation indicates that the follower radius should be close to the value given by the following equation:

$$R_3 = R_1 + 0.26(R_2 - R_1) \quad (2)$$

The proportions defined by Equation 2 tend to permit slight play during the initial and final portions of the cam stroke, but maintain accurate fit at the mid-point. That is the point at which the mechanism that is driven by the cam shifts from being accelerated to being decelerated. Accurate fit at that inflection point is particularly important for eliminating noise and vibration. In practice a follower radius exceeding the larger cam radius by approximately $\frac{1}{4}$ of the cam throw, in substantial accordance with Equation 2, has been found to be particularly satisfactory.

Particularly for cam stroke angles that are relatively small, as here described, the preferred proportions are such that the follower radii of curvature are approximately the larger cam radius or, specifically, that radius plus an amount that is equal to or somewhat less than $\frac{1}{2}$ the difference between the two cam radii, or plus an amount equal to approximately $\frac{1}{4}$ of that difference.

If the cam stroke angle is somewhat larger than described, it may be advantageous to provide cam followers having convex curvature that is not strictly circular, the radius of curvature having a value close to that given by Equation 1, for example, near the axial plane of movement (the plane of FIG. 4) and becoming slightly smaller with increasing distance from that plane. If it is preferred to maintain circular curvature of the follower surfaces, the cam action can be improved for relatively large cam throw by making the shift faces of the cam very slightly convex, thereby reducing or eliminating the play that may appear during the initial and final portions of the stroke when the follower radius approximates that of Equation 2. However, a great advantage of the invention is that remarkably good fit is obtainable with

circular follower surfaces and with cams comprising only concentric circular dwell surfaces and straight through surfaces. That is especially true for cams of small throw angles providing the very rapid stroke that is an outstanding characteristic of the present invention, together with the slow acceleration and deceleration of the cam driven element illustrated diagrammatically in FIGS. 17 and 18.

I claim:

1. In a kinetograph movement the combination of a cam driven element guided for back and forth movement along a predetermined path, 10 a rotative cam means mounted for rotation about a fixed axis and having two diametrically opposed peripheral circular arc portions of different radii centered on said axis and diametrically opposed substantially straight peripheral shift runs leading tangentially from the ends of the arc portion of smaller radius to the ends of the arc portion of larger radius, a pair of cam followers mounted in normally fixed spaced relation on the cam driven element, 15 said followers having opposing substantially circular cam engaging faces convexly curved toward the cam axis, the centers of said convex follower curvatures lying in substantial diametric opposition about the cam axis and their radii of curvatures being substantially that of the radius of the circular arc portion of larger radius of the cam means, 20 the relation between the smaller and larger cam radii and the curvature radius of the convex follower faces 30 being such as to closely oppositely engage the cam means throughout its periphery and to give the cam driven element a shift movement of slowly increasing and decreasing acceleration and deceleration.
2. The combination defined in claim 1 and in which the convex curvatures of said follower faces are circular and each of a radius approximately within the range between the larger cam radius and a value that exceeds the larger cam radius by about $\frac{1}{2}$ of the difference between the two cam radii. 35
3. The combination defined in claim 2 and in which, said cam means embodies two cam members axially spaced and rotating together, each of said cam members being of the form specified in said claim, and said cam followers being also axially spaced and each engaging a single one of said cam members. 40
4. The combination defined in claim 1 and in which, said cam means embodies two cam members axially spaced and rotating together, each of said cam members being of the form specified in said claim, and said cam followers being also axially spaced and each engaging a single one of said cam members. 45
5. The combination defined in claim 4 and in which said cam driven element is a film register means guided for reciprocating movement along a straight line. 50
6. The combination defined in claim 1 and in which the convex curvatures of said follower faces are circular and each of a radius approximately within the range between the larger cam radius and a value that exceeds the larger cam radius by about $\frac{1}{2}$ of the difference between the two cam radii, 55 and in which said cam driven element is a film register means guided for reciprocating movement along a straight line.
7. The combination defined in claim 6 and in which said film register means embodies 60 a register carrying shaft guided for longitudinal reciprocation along a line of movement transverse of the axis of cam rotation, and said cam followers being mounted on said shaft for normal movement therewith.
8. The combination defined in claim 1 and in which the convex curvatures of said follower faces are circular and each of a radius slightly larger than the 65

- larger of the radii of the two circular arc portions of the cam means
- said cam means embodies two cam members axially spaced and rotating together, each of said cam members being of the form specified in said claim, and in which said film engaging element is a film register means embodying a register carrying shaft mounted for longitudinal reciprocation along a line of movement transverse of the rotational axis of the cam means, the pair of cam followers being mounted on said shaft for normal movement therewith, and said cam followers being relatively displaced in a direction parallel to the rotational axis of the cam means commensurately with the axial spacing of the cams, so that each cam operatively engages only one of the followers.
9. The combination defined in claim 8 and in which, the follower members each include a portion directly mounted on said register shaft for axial movement thereon, and spring means acting on one of said portions and pressing said portions into mutual abutment axially of the register shaft.
10. The combination defined in claim 9 and also including a camming member mounted on the register shaft for rotation about the axis of that shaft against a shaft abutment, said spring means pressing the other of said follower portions axially against said camming member.
11. The combination defined in claim 1 and in which the cam driven element embodies a plate-like member carrying the pair of cam followers peripherally overhanging the cam means, and the convex curvatures of said follower faces are substantially circular and each of a radius slightly larger than the larger of the radii of the two circular arc portions of the cam means.
12. The combination defined in claim 1 and in which the convex curvatures of said follower faces are circular and each of a radius approximately within the range between the larger cam radius and a value that exceeds the larger cam radius by about $\frac{1}{2}$ of the difference between the two cam radii, said cam means embodies two cam members axially spaced and rotating together, each of said cam members being of the form specified in said claim, and said cam driven element embodying a plate-like member lying between said spaced cam members and carrying the two cam followers off-set from its opposite faces to each overhang one of the cam members.
13. In a kinetograph movement, the combination of a film engaging member guided for movement back and forth along a predetermined line of movement and embodying a plate-like member, a cam means rotatable about an axis normal to the plane of the plate-like member and embodying two cams axially spaced with said plate-like member between them, and a pair of cam followers integrated with and offset from opposite faces of the plate-like member to each peripherally overhang one of said cams.
14. In a kinetograph movement, the combination of a film engaging member guided for movement back and forth along a predetermined line of movement and embodying a plate-like member, a cam means rotatable about an axis normal to the plane of the plate-like member and embodying a flat cam, means holding the plate-like member flatly against said cam, and a pair of cam followers integrated with and offset from a face of the plate-like member to each peripherally overhang said cam,

each cam follower having a convex cam engaging face.

15. In a kinetograph movement, the combination of a film engaging element mounted for back and forth movement along a predetermined path,

a cam means mounted for revolution about a fixed axis, 5 said cam means having two diametrically opposed peripheral circular arc portions of different radii centered on said axis and diametrically opposed substantially straight peripheral shift runs leading tangentially from the arc portion of smaller radius to 10 the ends of the arc portion of larger radius,

a pair of cam followers mounted on the film engaging element in fixed spacing and having cam engaging faces in substantial diametric opposition about the cam axis, 15

said cam engaging faces being substantially circularly convexly curved toward the cam axis at substantially equal radii in the plane of rotation of the cam means, the radius of convexity of said cam engaging faces being of the order of the larger cam 20 means radius.

16. In a kinetograph movement the combination of a cam driven element guided for back and forth movement along a predetermined path,

a rotative cam means mounted for rotation about a 25 fixed axis and having two opposed peripheral and substantially circular arc portions of different radii centered on said axis and substantially straight peripheral shift runs leading tangentially from the ends of the arc portion of smaller radius to the ends of 30 the arc portion of larger radius,

a cam follower mounted on the cam driven element, said follower having a substantially circular cam engaging face convexly curved toward the cam axis and of a radius substantially that of the radius of 35 the circular arc portion of larger radius of the cam means, the relation between the smaller and larger cam radii and the curvature radius of the convex follower face being such as to engage the cam means

throughout its periphery and to give the cam driven element a shift movement of slowly increasing and decreasing acceleration and deceleration.

17. In a kinetograph movement the combination of a cam means mounted on and for rotation about the axis of a rotatable driving shaft,

a register carrying shaft mounted for longitudinal reciprocation along a line of movement transverse of the axis of said shaft,

a cam follower means mounted on said register shaft for longitudinal sliding movement thereon,

two abutment members mounted on said register shaft and spaced longitudinally from the opposite ends of the cam follower means,

a spring seated on one said abutment and pressing against the adjacent end of the follower means tending to move said follower means longitudinally away from said one abutment,

and a camming member mounted on the register shaft for rotation about the axis of that shaft, said camming member bearing against the other of said abutments and having camming action on the adjacent end of said follower means to move that means longitudinally against the action of said spring when rotated about the axis of the register shaft,

said cam follower means comprising two substantially identical follower members mounted in longitudinal abutting relation on said register shaft and engaging opposite peripheral portions of the cam means.
